DES. 2227

Greenleaf, Everett, of Leominster, Mass.

Letters Patent No. 3,227. Dated Decr. 5, 1865.

Ante-dated November 18, 1865.

Design for a Trade Mark.

The schedule referred to in these Letters Patent and making part of the same.

To all Persons to whom these Presents shall come:

Be it known that I, Greenleaf,

L. Everett, of Leominster, of the County of Worcester, and State of Massachusetts, have invented or produced a new and useful Design for a Trade Mark, and do hereby declare the same to be represented in the accompanying drawing and thus described:

It consists of two triangles A & B, a straight line C, two circles A & B, and an ellipse or oval arranged together as represented in the said drawing.

I claim as my invention the design for a trade mark as herein described and represented in the accompanying drawing.
